(57) **CLAIM**

The ornamental design for a storage box, as shown and described.

DESCRIPTION

FIG. 1 is a top front perspective view of a storage box showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom front perspective view thereof;

FIG. 9 is a bottom rear perspective view thereof;

FIG. 10 is a cross-section view thereof, taken along line 10-10 of FIG. 8;

FIG. 11 is an enlarged section 11 of FIG. 10;

FIG. 12 is an enlarged section 12 of FIG. 10;

FIG. 13 is a cross-section view thereof, taken along line 13-13 of FIG. 8;

FIG. 14 is an enlarged section 14 of FIG. 13; and,

FIG. 15 is an enlarged section 15 of FIG. 13.

The dot-dash lines in FIG. 8 represent the cutting plane lines. The dot-dash lines in FIG. 10 to FIG. 15 represent the designation of enlargement views. None of the dot-dash lines form part of the claimed design.

1 Claim, 13 Drawing Sheets
